UNITED STATES PATENT OFFICE.

GEORGE F. JOHNSON, OF PHILADELPHIA, PENNSYLVANIA.

IMPROVEMENT IN LOCOMOTIVE-BOILERS.

Specification forming part of Letters Patent No. 38,584, dated May 19, 1863.

To all whom it may concern:

Be it known that I, G. F. JOHNSON, of Philadelphia, Pennsylvania, have invented an Improvement in Locomotive-Boilers; and I do hereby declare the following to be a full, clear, and exact description of the same, reference being had to the accompanying drawings, and to the letters of reference marked thereon.

My invention relates to that class of locomotive-boilers in which a chamber, generally termed a "combustion-chamber," is formed in the body of the boiler, between the fire-box and the front tube-plate; and my invention consists in introducing a jet or jets of steam into the said combustion-chamber immediately in front of the said tube-plate, and directing the said jet or jets of steam toward the fire-box, so that the said combustion-chamber may be always free from the accumulation of partly-consumed coke and cinders, which tend to choke up the tubes and to interfere with the draft, but which, when forced back into the fire-box in small quantities, are available as fuel.

In order to enable others skilled in the construction of locomotives to make my invention, I will now proceed to describe a mode of carrying it into effect which I have found most efficacious in practice.

On reference to the accompanying drawings, which form a part of this specification, Figure 1 is a vertical section of a locomotive-boiler with my improvement, and Fig. 2 a transverse section on the line 1 2, Fig. 1.

A represents the body or cylindrical portion of the boiler, B being the smoke-box; C, the rear tube-plate; D, the fire-box; E, the combustion-chamber, and F the front tube-plate.

In coal-burning locomotives the formation of a chamber at the rear of, and communicating with, the fire-box, and between the latter and the front tube-plate, has been found expedient for the more thorough combustion of the carbonaceous gases which would otherwise pass in an unconsumed state through the tubes. The only objection to this so-called "combustion-chamber" is the accumulation therein of masses of partly-consumed coke and cinders, which tend to choke the tubes, and which must necessarily be removed from time to time by a suitable instrument inserted through the door of the fire-box, an operation requiring considerable exertion and tending to interfere with the proper burning of the fuel.

I secure to the body of the boiler, near the rear of the same, an ordinary cock, G, which communicates with the steam-space in the boiler and with a pipe, H, which passes down through the smoke-box and communicates with one of the lowest tubes, H'. To the plug of the cock G is secured a lever, I, to which is attached a rod, or other suitable mechanism, to enable the engineer to turn the cock without moving from his position in front of the fire box. Whenever any quantity of coke and cinders has accumulated in the combustion-chamber the engineer opens the cock and causes a jet of steam to pass down the pipe H, through the tube H', and to escape into the combustion chamber at the rear of the accumulated cinders, which are forced by the jet into the fire-box. This opening of the cock may be repeated at such intervals as may be deemed necessary for keeping the combustion-chamber clear of all particles of coke and cinders. As the latter are discharged into the fire-box in small quantities, they are available as fuel, and cannot interfere with the proper combustion of the fuel, which is the case when large masses of cinders and refuse are raked from the combustion-chamber in the usual manner.

Although I have illustrated and described a particular mode of discharging a jet or jets of steam into the combustion-chamber, it will be evident that jets may be discharged into the said chamber without the aid of the lower tube or tubes, and by pipes arranged in a variety of ways. I therefore do not desire to confine myself to the specific mode herein described of admitting jets of steam to the combustion chamber; nor do I desire to claim, broadly, maintaining the flues of locomotive-boilers free from cinders and ashes by jets of steam; but

I claim as my invention and desire to secure by Letters Patent—

A jet or jets of steam introduced into the combustion-chamber of a coal-burning locomotive boiler, at the rear of the said chamber, when the jet or jets are directed toward the fire-box, as set forth, for the purposes specified.

In testimony whereof I have signed my name to this specification in the presence of two subscribing witnesses.

GEORGE F. JOHNSON.
